(57) **CLAIM**

The ornamental design for a cup washer, as shown and described.

DESCRIPTION

FIG. 1 is a perspective view of a cup washer, showing my new design;

FIG. 2 is another perspective view thereof;

FIG. 3 is a front elevational view thereof;

FIG. 4 is a rear elevational view thereof;

FIG. 5 is a left elevational view thereof;

FIG. 6 is a right elevational view thereof;

FIG. 7 is a top plan view thereof;

FIG. 8 is a bottom plan view thereof; and,

FIG. 9 is an enlarged detail view of area designated 9 shown in FIG. 1.

The broken lines illustrate portions of the cup washer and form no part of the claimed design. The dot dashed broken lines shown in FIGS. 1 and 9 indicate cutoff boundaries for the enlarged detailed portion views and form no part of the claimed design.
